ELECTRON DISCHARGE TUBE

Nils E. Lindenblad, Port Jefferson, N. Y., assignor
to Radio Corporation of America, a corpora-
tion of Delaware

Original application April 14, 1932, Serial No.
605,274. Divided and this application May 14,
1936, Serial No. 79,648

1 Claim. (Cl. 250—27.5)

This invention relates to a novel electron dis-
charge tube for use in ultra high radio frequency
signalling.

In tubes used hereinbefore to relay or amplify
ultra high frequency oscillations, numerous diffi-
culties have been encountered due to the internal
capacity coupling between the several electrodes
enclosed in the envelope of the tube, also due to
the impossibility of providing low impedance leads
from the tube elements in conventional tube de-
sign. This inter-electrode capacity is the cause
of many undesirable effects. The use of a tube
in which the inter-electrode capacity is present,
even when compensated, is attendant with many
serious disadvantages.

Many schemes have been devised to counteract
or compensate the effect of this internal capacity.
In some arrangement, neutralizing capacities are
placed at appropriate points external to the tube
envelope and between the desired electrodes di-
rectly or throughout the interconnecting circuits
to compensate or to counteract the effect of the
inter-electrode capacity. While it is true that
these neutralizing capacities were to some extent
effective to counteract the internal capacity or to
negative the effect of the internal capacity be-
tween electrodes and to de-couple the input and
output circuits, they are not entirely satisfactory
at very high frequencies since the neutralizing ca-
pacities themselves, together with sufficient
amounts of inductance, which is inherent and
thus unavoidable, form new paths in which free
oscillations can develop at some other, sometimes
only slightly different, frequency. Thus, for very
high frequencies, neutralizing, or rather bal-
ancing, can only be accomplished for one par-
ticular frequency at the time. As there is nothing
to prevent the circuits from choosing these free
oscillations, they provide a serious problem which
offsets the advantages gained by the use of neu-
tralizing capacities. Furthermore, these neutral-
izing capacities are usually added as directly as
it is possible (outside the tube envelope) to the
internal capacity between the electrodes in the
tube and thereby contribute to a decrease in the
maximum frequency, which can otherwise be re-
layed or amplified by the thermionic tube and its
associated circuits. This decrease being due to in-
creased total capacity with resulting lower capaci-
tive reactance which holds down the voltage swing
of the electrodes.

In other cases, tubes of the screen grid type
were used. It was found that even these tubes
and their associated circuits became very un-
stable in operation where ultra high frequencies

were to be relayed or amplified, because of the
difficulty of providing a low inductance, low ca-
pacity lead from the screen to ground.

All of the above disadvantages are obviated in
accordance with the present invention by the use
of a novel thermionic tube wherein the envelope
comprises two vitreous portions separated by a
metallic ring having an extending flange, the ring
being connected with the grid electrode which is
disposed somewhere near the median line of the
ring and of the envelope. The anode electrode is
disposed in one of the vitreous bulbs of the tube,
and the heated cathode is disposed in the other
vitreous bulb of the tube.

By the use of the novel tube, as described above, 15
in a push-pull circuit in which the grid electrode is
maintained at a constant potential and the cath-
ode electrode is swung or oscillated at ultra high
frequency with respect to the grid electrode, ex-
tremely stable and satisfactory operation may be 20
obtained. Furthermore, the use of such arrange-
ment permits higher frequencies to be relayed or
amplified than has been heretofore possible.

Stable operation of thermionic relays and am-
plifiers, at frequencies where conventional neu-
tralizing methods are successful, is also obtained
in accordance with the disclosure set forth in my
United States application #605,274 filed April 14,
1932, of which this application is a division, by
the use of a tube of the type heretofore known 25
in the art, or by the use of a tube constructed in
accordance with the present invention in a new
and improved circuit in which the elements of
the circuit are so arranged that the circuits bal-
ance themselves without the use of neutralizing 30
capacities or equivalent oscillation suppressing
or preventing means.

The novel features of the thermionic tube have
been pointed out with particularity in the claim
appended hereto.

The nature of the tube and of the use of the
same in circuit arrangements, will be clear to the
reader from the following detailed specification,
and therefrom when read in connection with the
attached drawing, throughout which like refer-
ence characters indicate like parts, and in which:

Figures 1 and 1a show practical embodiments of
my novel thermionic tube; while

Figure 2 shows, for purposes of illustration, an
ultra high frequency relay circuit in which a pair
of tubes, as illustrated in Figures 1 or 1a, are in-
corporated.

Referring to Figure 1, T indicates a thermionic
tube having vitreous portions 1 and 2 which are
closed at the ends 3 and 4 by re-entrant portions

5 and 6 respectively. The open ends 7 and 8 of the vitreous portions 1 and 2 are sealed in shallow channels on opposite faces of annular metallic ring member 10 shown in the drawing as a substantially flat washer or disc with a central opening smaller in diameter than and concentric with the wall of the envelope. The peripheral portion 12 of metallic member 10 is provided with bolt holes 14 therein as shown in Figure 1, or 10 a threaded periphery, as shown in Figure 1a.

The outer ring-shaped portion 12 permits mounting of the tube T. The grid electrode 16 of thermionic tube T is suspended within the opening in the ring member 10. The specific nature of this grid forms no part of the present invention and need not be discussed in detail here. The grid, however, may be of any known shape or structure. The cathode or filament electrode 18 is supported in the re-entrant portion 5 of the bulb 1 while the anode electrode 20 is supported in the re-entrant portion 6 of the member 2. It will be obvious that if the ring 12 is mounted in an opening in a metallic sheet or support 22 by bolts as in Figure 1 or by threads as in Figure 1a, and in any manner as shown in Figure 2, the electrode 18 may be electrostatically isolated from the electrode 20 to a very high degree by means of the grid 16 and ring 12. Further, the resistance of the grid lead-in conductor or ring 12 between the electrode and the external connection is reduced to a minimum because of its substantially flat washer-like shape. Ultra-high frequency currents, which my improved tube is designed to generate and amplify, flow only on the surface of the ring, and the impedance to the flow is approximately proportional to the length of the conducting path along the surface of the ring. The length of the path between the inner and outer peripheries of the annular lead-in conductor or ring is a minimum and the impedance between the peripheries is a minimum when the conductor is substantially flat. Ring member 12 is substantially flat and is provided on either face with shallow channels for receiving the ends 7 and 8 of the vitreous portions of the envelope.

In Figure 2 I have shown a symmetrical relay circuit which includes two thermionic tubes T and T', each constructed as illustrated in Figures 1 and 1a. Each of these tubes is fixed by its ring 12 to a metal partition member 22 dividing the metal shielding closure member or box 24 into two separate portions. The cathode 18 of T and cathode 18' of T' are heated from any alternating current source through transformers 26 and 26', each having a symmetrical secondary winding, the outer terminals of which are connected to the cathodes 18 and 18' respectively, and the electrical midpoints 25 and 27 of which are connected to the terminals of an input circuit 30 comprising variable capacity C and inductance I. The input circuit 30 is tuned to the frequency of the incoming signal by means of the inductance I and the capacity C. The incoming signal, which may be derived from any source of ultra high frequency oscillations, is impressed on the inductance I by means of the inductance 21 coupled thereto. Biasing potential to maintain the cathodes 18 and 18' at the desired operating potential relative to grid electrodes 16 and 16' is provided by connecting the midpoint of inductance I through a lead 23 to a source of biasing potential BP having

one terminal grounded as shown. The anodes 20 and 20' of the thermionic tubes T and T' are connected as shown in a tank circuit TC comprising a tuning capacity C₂ and inductance 30'. Oscillations appearing in the tank circuit TC are conveyed to any work circuit by means of an inductance 32 inductively coupled to inductance 30'. Charging potential for the anodes 20 and 20' is provided by a lead 31 connected on the one hand with the midpoint of the inductance 30' 10 and on the other hand to the positive terminal of a source 34 having its negative terminal connected to ground. In order to prevent any radio frequencies appearing in the input circuit 30 from being introduced into the source of alternating 15 current used to heat the cathodes 18 and 18', the leads 25 and 27 are connected at a point between pairs of radio frequency shunting condensers 11 and 13 and 15 and 17 respectively connected in parallel with the secondary winding of transformers 26 and 26'.

In operation, the high frequency oscillations are impressed from the source through winding 21 to the input circuit 30 of the thermionic tubes T, T'. The grids of these tubes are maintained at a constant potential lower than the potential of the cathodes. The grids may be at ground potential. The cathodes 18 and 18' of the tubes oscillate at the fundamental frequency of the ultra high frequencies to be relayed with respect to the grid electrodes. The oscillating potentials at the frequency to be relayed appearing on the anodes 20 and 20' are set up in the tank circuit TC from which they are led by means of inductance 32 to any work circuit.

It has been found that by maintaining the grids at an alternating current potential lower than the potential of the cathode, or by grounding the grid electrode as to alternating current potentials, extremely stable operation is obtained. 40 It has further been found that by mounting the tubes, as shown in Figure 2, not only are the anodes and cathodes of the tubes shielded from each other to a high degree, but the output and input circuits of the relay system are electrically separated.

The arrangement of Figure 2 may be used as a frequency multiplier. If the arrangement of Figure 2 is used as frequency multipliers the anodes of the tubes may be connected in parallel or push-push relation. The arrangement for frequency multiplication in other respects may be as shown in the drawing.

I claim:

An electron discharge device comprising a cathode and an anode, a sealed envelope enclosing the electrodes comprising two cylindrical envelope portions of insulating material, a lead-in conductor of minimum impedance to high frequency currents between connections inside and outside said envelope comprising a substantially flat metal disc with a central aperture of less diameter than the inside diameter of the envelope, the rims of the cylindrical envelope portions being sealed to opposite faces of the disc intermediate the edge of said central aperture and the periphery of the disc, and a grid-like electrode interposed between said cathode and anode and attached to said disc.
